UNITED STATES PATENT OFFICE.

MILLER REESE HUTCHISON, OF SUMMIT, NEW JERSEY.

DESIGN FOR A DIAPHRAGM CASE AND RESONATOR FOR DIAPHRAGM-ACTUATED HORNS.

No. 39,801.

Specification for Design.

Patented Feb. 2, 1909.

Application filed October 8, 1908. Serial No. 456,838. Term of patent 7 years.

To all whom it may concern:

Be it known that I, MILLER REESE HUTCHISON, a citizen of the United States, residing at Summit, in the county of Union and State of New Jersey, have invented a new, original, and ornamental Design for a Diaphragm Case and Resonator for a Diaphragm-Actuated Horn, of which the following is a specification, reference being had to the accompanying drawing, forming part thereof.

The figures of the drawing show the design of the article.

Figure 1 is a side elevation showing the resonator and diaphragm casing; Fig. 2 is an end elevation showing how the longitudinal section of the resonator varies.

I claim:

The ornamental design for diaphragm case and resonator for a diaphragm actuated horn, as shown.
